UNITED STATES PATENT OFFICE

ERNEST J. SCHUDA, OF ERIE, PENNSYLVANIA, ASSIGNOR TO LOVELL MANUFACTURING COMPANY, OF ERIE, PENNSYLVANIA, A CORPORATION OF PENNSYLVANIA

WRINGER

Application filed January 9, 1928. Serial No. 245,306.

This invention is designed to improve wringers, particularly in relation to the mounting of the upper roll in such a manner that the removal of the top bar of the wringer will carry with it the roll and its bearing. The invention is an improvement on the structure set forth in my application executed on the 17th day of December, 1927. Features and details of the invention will appear from the specification and claims.

A preferred embodiment of the invention is illustrated in the accompanying drawings as follows:

Fig. 1 shows a front elevation, partly in section.

Fig. 2 an enlarged perspective view of the connection between the top bar and the upper roll.

Fig. 3 a perspective view of the strap forming the connection.

Fig. 4 a perspective view of the upper bearing block.

Fig. 5 a section on the line 5—5 in Fig. 1. 1 marks the base of the frame and 2 the side stiles. The side stiles are preferably of channel form and carry the bearing blocks 3 and 4 for the bottom and top rolls 5 and 6. A spring 7 operates on the upper bearing block. It is engaged by a pin 8. The pin 8 extends through a sleeve 9 mounted in a top bar 10 and is provided with a shoulder 8^a. The sleeve 9 has the side slots 9^a through which the shoulder may be released and is provided with cam surfaces 11 at its bottom end for adjusting the tension of the spring. An arm 12 is secured to the pin 8 by means of which it may be rotated to release the tension on the spring.

The side stiles are provided with notches 13. These are engaged by latches 14, one at each side of the wringer. The latches are mounted on pins 15 extending through the top bar 10. The latches have the cross member 16 which is in the path of the spring 7 when the release device is actuated to release the tension on the spring. This operating the latches releases the top bar and thus permits of the entire removal of the top roll and thus gives an unlimited clearance between the rolls. The latch has a stop projec-

tion 17 which engages the top bar and positions the shoulder of the latch. These parts are shown in my prior application above referred to.

The block 4 is provided with grooves 18 in its sides and a strap 19 bent flatwise into U form is arranged in the grooves 18, the cross member of the strap passing under the block and under the rod 20 of the upper roll. The upper ends of the straps have arms 21 with slots 22, the pin 15 extending through the slots. This makes a very simple and efficient strap hooking up the block, the upper roll and top bar. The thickness of the strap is entirely taken care of in the groove 18 so that it takes no added space and bent as it is flatwise of the metal may be very readily and easily fabricated.

What I claim as new is:

1. In a wringer, the combination of a frame comprising side stiles; top and bottom rolls having roll shafts; bearing blocks for the top roll shaft yieldingly supported with relation to the top bar and slidably mounted in the side stiles; a top bar; sheet metal straps bent flatwise into U shape and extending around the blocks and upper roll shaft; and connections between the top bar and the straps.

2. In a wringer, the combination of a frame comprising side stiles; top and bottom rolls having roll shafts; bearing blocks yieldingly supported with relation to the top bar and slidably mounted in the side stiles, said blocks having grooves in the sides thereof; a top bar; a U-shaped strap having its sides in the grooves of the blocks and the bottom bar of the strap under the top roll shaft; and connections between the upper end of the strap and the top bar.

3. In a wringer, the combination of a frame comprising side stiles; top and bottom wringer rolls having roll shafts; bearing blocks for the top roll shaft slidably mounted in the side stiles; a top bar; tension means exerting tension on the rolls; a safety release device releasing tension on the rolls; locking means securing the top bar to the stiles, said locking means comprising a latch; means to actuate the latch as the tension on

the rolls is released; and straps extending around the bearing blocks and under the top roll shaft, said straps being of U-shape secured with the latch on the top bar.

⁵ In testimony whereof I have hereunto set my hand.

ERNEST J. SCHUDA.
